UNITED STATES PATENT OFFICE.

FRANK H. STANWOOD, OF ARLINGTON, MASSACHUSETTS, ASSIGNOR TO STANWOOD EQUIPMENT COMPANY, A CORPORATION OF MAINE.

NON-SLIPPING TREAD.

1,257,144.

Specification of Letters Patent. Patented Feb. 19, 1918.

Application filed June 14, 1916. Serial No. 103,605.

To all whom it may concern:

Be it known that I, FRANK H. STANWOOD, a citizen of the United States, residing in Arlington, in the county of Middlesex and 5 State of Massachusetts, have invented a new and useful Improvement in Non-Slipping Treads, of which the following is a specification.

This invention relates in general to non-slipping treads adapted for use in tread or working surfaces, such as stair steps, walks, runways and the like, a particular use of the invention, however, being in connection with the running boards for automobiles 15 and other vehicles, although it will be manifest as the invention is better understood that it has a much wider and broader application.

A principal object of this invention is the 20 provision of a non-slipping tread for automobiles and the like which may be supplied to the automobile maker or user in units ready for instant application requiring only the fastening of the unit in desired location.

25 A further object of the invention is the provision of such an article which will consist essentially of a central or body sheet of metal coated with a non-slipping ribbed surface so united with a central body sheet 30 as to restrain any movement of the non-slipping coating in service, the union between the body or central sheet and the coating being so produced as to reduce the wearing of the coating material to a minimum.

35 Other objects and advantages of the invention will be apparent as it is better understood from the following description when considered in connection with the accompanying drawing illustrating a preferred embodiment thereof.

On the drawing,

Figure 1 is a perspective view of a non-slipping tread embodying my present invention;

Fig. 2 is a bottom plan view of the same with a part of the coating broken away;

Fig. 3 is a section taken on the line 3—3 of Fig. 1;

50 Fig. 4 is a section on the line 4—4 of Fig. 1.

For the purpose of illustrating my pres-

ent invention, I have shown on the drawing a non-slipping tread which is comprised of a central metal body sheet 6 coated with a 55 non-slipping composition, preferably rubber as will be now described. The sheet 6 is provided with apertures 7, through which screws, rivets or other fastening means may be inserted, and is otherwise preferably imperforate. The coating of non-slip material is molded about the sheet and is formed to provide two series of elongated parallel upwardly extending ribs 8. The material of the coating 8 extends completely about 65 the body sheet 6 forming a layer 9 beneath it, inclosing its edges at 10 and covering its upper face to provide the parallelly extending ribs 8. The ribs 8 are preferably arranged in two parallelly extending series 70 each composed of ribs extending from an end of the plate inwardly to adjacent its transverse center in parallelism.

The plate 6 is coated with a material which will cause the rubber or other composition to be secured firmly to the plate throughout the contacting area of the two materials. The internal or securing coating is preferably of some chemical composition containing copper which has a 80 marked affinity for the iron of the plate and the rubber of the composition. A substance well designed to accomplish the purposes of my present invention is copper sulfate, which is preferably lightly painted 85 with a brush or otherwise upon the plate. In practice as little as possible of this sulfate is used, indeed, in the finished plate preferably no copper or copper sulfate is visible, the intermediate holding material 90 merely apparently soiling the plate. By its use mechanical interlocking of the rubber and metal is rendered unnecessary and the pressure felt by the tread pads or ribs 8 is transmitted against the smooth upper 95 surface of the plate without encountering any edges, corners or projections of the plate which would tend to cut into the rubber in continued service. The use of this material holds the rubber covering with 100 its upstanding ribs tightly to the plate so that there is no lever action or bending movement of the rubber parts when the ribs are in action under the foot of a user,

The coating of the plate permits of use of relatively thin rubber portions between the ribs since the connection thus provided between the ribs and the plate is sufficient to prevent the ribs bending over and tearing away.

10 The plate coated with green or unvulcanized rubber is placed in a mold and suitable pilots or pins extend through the opening 7 to prevent their closure by the rubber. The heat is then applied and the rubber vulcanized to the plate by reason of the presence of the copper in the internal securing coating.

15 It is thought that the invention and many of its attendant advantages will be apparent from the foregoing without further description, and it will be obvious that various changes may be made in the form of the article and in the form and construction and arrangement of its parts without departing from the spirit of the invention or sacrificing any of its material advantages,

the form hereinbefore described being merely a preferred embodiment thereof. 2.

I claim:

A non-slipping tread comprising an internal metal plate and a covering of rubber above and beneath said plate and vulcanized thereto, the portion of the covering above said plate having upstanding isolated ribs connected at their bases by the upper part of said covering the latter adhering by said vulcanization to the top of the plate between the ribs, the vulcanization of the material of the covering beneath said ribs and between said ribs and the material of the covering between said ribs serving together to restrain the ribs against displacement in service. 30 35

Signed in the presence of two subscribing witnesses.

FRANK H. STANWOOD.
